ATELIERS OTIS PIFRE, OF PARIS, FRANCE.

SYSTEM OF HAULAGE.

1,346,447.

Specification of Letters Patent. Patented July 13, 1920.

Application filed July 25, 1919. Serial No. 313,398.

To all whom it may concern:

Be it known that I, ERNEST ALPHONSE DERUNGS, of 1 Place de Wagram, Paris, France, engineer, have invented Improved Systems of Haulage, of which the following is a full, clear, and exact description.

In haulage systems with fixed cables, adhesion is generally secured by passing the cable around one or more pulleys carried by the propelled device. This method of operating has the disadvantage that of excessive wear of the cables, on the one hand because of the strain produced by bending them around curves of small radius and the resulting effects of flexion produced in the outer strands, and on the other hand because of the slip and friction resulting from insufficient adhesion.

Another disadvantage is the loss of energy corresponding with the effort required to overcome the rigidity of the cable and the friction.

The object of the present invention is to overcome these drawbacks and to relieve the cable from all stress other than that resulting from its own weight and from the effort of traction so that it is no longer necessary to protect or reinforce the cable, which can therefore be of any construction whatsoever.

The invention comprises the combination of stops, arranged at intervals along the cable, with coupling devices, carried by the tractor and engaging said stops to effect the propulsion of the tractor.

A further feature of the invention is the provision of means for automatically engaging the clips, or equivalent members, of the coupling device with, or detaching them from the stops on the cable, in such way as not to exert any lateral strain on the cable.

The invention is illustrated by way of example in the accompanying drawings in which: Figure 1 is a diagram showing the essential arrangement of the haulage system. Fig. 2 shows, diagrammatically, a method of carrying out the invention. Figs. 3 and 4 are respectively a vertical section and a plan of Fig. 2, and Figs. 5 and 6 are respectively a side elevation and a plan of a modification.

As shown the new system, in its entirety, comprises a fixed cable *a* on which members *b*, constituting stops, are secured at uniform intervals. A tractor *c* runs on the ground,

or on a track parallel to the cable, or moves on the water and is provided with guide pulleys *d*, which engage the cable and insure the relative position of the cable and tractor. The tractor is provided with an endless chain *e* passing over draft pulleys *f* driven by a motor of any kind whatsoever (not shown). One of these pulleys may serve to keep the chain taut.

Clips *g*, adapted to engage with the stops *b*, are mounted at intervals on the chain *e*, the distance between two successive clips being slightly greater than that separating two of the stops *b*. The clips are mounted on rocking supports, so as to be held at right angles to the chain while they are in engagement with the stops and so as to move out of the way automatically when the time arrives for them to be disengaged from the stops.

As the pulleys *f*, driven by any motor whatsoever are revolved in the direction indicated by the arrows, the chain *e* brings each of the clips *g*, which it supports or propels, successively into position adjacent the cable, a little in front of a stop *b*.

Once a clip has engaged with a stop, it remains in engagement therewith until the carriage has moved forward, in the direction of the arrow 1, through a distance equal to the distance between two clips whereupon said clip moves out of the way, for example by tilting, at the moment when next clip has just come into position in front of the next stop.

As will be readily understood, the stops alone take up the tractive effort and transmit it uniformly to all the strands of the cable, without subjecting the latter to any deformation. The cable therefore operates under the most favorable conditions possible, and may be of any construction whatsoever. It no longer requires any protection, or even reinforcement, such as is required when the cable passes around pulleys. The cable can remain perfectly rectilinear, the stop not subjecting it to any lateral strain.

In the method of carrying out the invention shown in Figs. 2 to 4, which is particularly applicable in the case of devices intended to work at high speed, the clips *g* are in one piece with the tilting carriages *h*, provided with guide rollers *i* and connected to the chain *e* by rigid or elastic attach-

ments *j*. The rollers run between the rails *k* *k*¹ which keep the clips at right angles to the cable all the time they are intended to be in engagement therewith.

5 One portion *l* of the rail *k* is movable and is adapted to turn downward, as shown on the left of Fig. 2 by pivoting on an axis *l*². This portion of the rail being thus brought into the open position, the rear rollers of 10 the tilting carriage on arriving at the end of the straight section of the rail *k*, drop suddenly into the empty space thus formed, and the carriage tilts instantly on its other rollers, causing the release of the clip *g* by 15 a slight movement of recoil.

When they engage the cable, the clips slip into position automatically, since they are cut away in the shape of a fork, as shown in Fig. 3. To prevent any shock on the 20 next clip which engages a stop at the moment the preceding one is disengaged, the attachments may be provided, if desired, with a spring and a shock absorber, the latter responding more particularly to compression; in order not to interfere with the 25 recoil movement necessary for disengaging the clip.

The device may run in the opposite direction to that indicated: all that is necessary 30 for this purpose being to close the movable portion *l* and open the symmetrical movable portion *l*¹. This operation can be avoided by shaping the profile of the rail *k*, at both ends as represented by the dotted line *l*².

35 Figs. 5 and 6 relate to another method of carrying out the invention, applicable, more particularly, to slow speed work. The clips *g* are pivoted directly on the chain *e*; each clip is provided with a tail *m*, which is engaged by two abutments *n*, pivoted at *n*¹ and *n*² on the chain, one of the pivots having a slight play for the purpose of compensation for variations in the length of the chain between the points *n*¹ and *n*², according as it is straight or curving around the pulleys.

40 When the clip is on a rectilinear portion of the chain, the two abutments adjacent to a clip act simultaneously on the tail piece of the latter and keep the clip at right angles to the chain. When the leading abutment arrives at that portion of the chain which is curved around the pulley it takes up the position indicated on the left of Fig. 5, and 45 the clip tilts and disengages itself from the cable. The succeeding clip straightens itself, by a similar movement, on arriving in front of the stop *b* with which it is to engage.

50 The guide pulleys are not indispensable, but they have the advantage of preventing vibration of the cable and taking up any swaying so that the cable is always into position exactly over the clips.

55 The diagrammatic arrangement described

are given merely to crystallize the idea. The invention may be modified in various ways in carrying it out, the cable, for instance, being replaceable by a rigid rod, a chain, or other equivalent system, or by a sheaf of 70 cables operating in parallel or alternatively with one or more endless chains; the apparatus may also be arranged for several clips and stops to engage at the same time.

The lower portion of the endless chain 75 may be utilized for reversing the direction of running, by causing it to act on the same cable or on a second cable. The clips or equivalent members may turn on axes arranged in any manner whatsoever. 80

Claims:

1. In a system of haulage, a fixed cable, stop balls on the cable, a tractor, an endless chain carried by the tractor, clips carried by the chain, adapted to strike the stop balls 85 of the cable to produce propulsion.

2. In a system of haulage, a fixed cable, stops along this cable, a tractor, an endless chain carried by the tractor, coupling means carried by this chain and coöperating with the stops of the cable to produce propulsion, 90 means for engaging with the said stops and automatically disengaging the coupling members.

3. In a system of haulage, a fixed cable, 95 stop balls along this cable, a tractor, an endless chain coöperating with the stops of the cable to produce propulsion, with the aid of clips carried by this chain, in a manner to produce propulsion and checking of the 100 tractor in the two ways of running, the stops and clips being spaced apart on the cable and chain, the distance between two successive clips being slightly greater than that separating two of the stops. 105

4. In a system of haulage, a fixed cable, stops along this cable, a tractor, an endless chain carried by the tractor, rocking clips carried by the chain, adapted to engage with the stops of the cable, means for automatically raising the clips and moving them out of the way, tilting carriages carrying the clips, connected by attachments to the endless chain. 110

5. In a system of haulage, a fixed cable, 115 stops along this cable, a tractor, an endless chain carried by the tractor, rocking clips carried by the chain, adapted to engage with the stops of the cable, means for automatically raising the clips and moving them out 120 of the way, tilting carriages with rollers carrying the clips, connected by attachments to the endless chain, and guide rails for the rollers with an interrupted portion producing the tilting of the clips. 125

6. In a system of haulage, a fixed cable, stops along this cable, a tractor, an endless chain carried by the tractor, rocking clips carried by the chain, adapted to engage with the stops of the cable, means for auto- 130

matically raising the clips and moving them out of the way, tilting carriages with rollers carrying the clips, connected by attachments to the endless chain, guide rails for the 5 rollers with hinged parts opening and closing for causing the tilting at the required point.

7. In a system of haulage, a fixed cable, stops along this cable, a tractor, an endless 10 chain carried by the tractor, rocking clips carried by the chain, adapted to engage with the stops of the cable, elastic attachments connecting the said clips to the chain, shock absorbers combined with these attachments.

15 8. In a haulage system, a fixed cable, stops on this cable, a tractor, an endless chain, rocking clips carried by the chain and adapted to engage with the stops of the cable.

20 9. In a haulage system, a fixed cable, stops on this cable, a tractor, an endless chain, rocking clips carried by the chain and adapted to engage with the stops of

the cable, means for automatically raising the clips and moving them out of the way. 25

10. In a haulage system, a fixed cable, stops on this cable, a tractor, an endless chain, clips carried by this chain and describing a twofold movement of tilt and recoil. 30

11. In a haulage system, a fixed cable, stops on this cable, a tractor, an endless chain, rocking clips carried by the chain and adapted to engage with the stops of the cable, elastic attachments connecting the 35 said clips to the chain.

12. In a system of haulage, a fixed cable, stop balls spaced apart on the cable, a tractor, an endless chain carried by the tractor, clips carried by the chain and adapted to 40 strike the stop balls.

The foregoing specification of my improved system of haulage, signed by me this twenty-third day of June, 1919.

ERNEST ALPHONSE DERUNGS.
